MANUFACTURE OF MOTOR FUELS

Louis A. Clarke, Fishkill, and Frank Henry Bruner, Ernest F. Pevere, and George B. Hatch, Beacon, N. Y., assignors, by mesne assignments, to The Texas Company, New York, N. Y., a corporation of Delaware

Application March 8, 1939, Serial No. 260,490

8 Claims. (Cl. 260—683.4)

This invention relates to the manufacture of motor fuels such as gasoline and has to do particularly with the production of high antiknock saturated gasoline hydrocarbons by the alkylation or condensation of low boiling isoparaffins, for example isobutane and isopentane, with olefins or polymers thereof in the presence of concentrated sulfuric acid as a catalyst.

The alkylation of low boiling isoparaffins, such as isobutane or isopentane, with C₄ olefins or a mixture of C₄ and C₅ olefins takes place readily in the presence of concentrated sulfuric acid of about 90 to 98% strength, and preferably about 94%, when the amount of isoparaffins is in excess of that of the olefins, preferably between three and five times that of the olefins by weight, at ordinary temperatures, for example 50 to 90° F. in the liquid phase.

The propylene containing hydrocarbons, which have been proposed for alkylation heretofore, have contained relatively large amounts of C₄ olefins. For example, cracking still gases or refinery gases, ordinarily contain as much C₄ as C₅ olefins, and often the C₄ olefins are in considerable excess, such as twice the amount of the propylene.

It is often important to be able to alkylate C₃ olefins containing considerably smaller amounts of C₄ olefins than contained in ordinary refinery products. Thus gaseous products from special processes such as catalytic polymerization, dehydrogenation of propane, special fractionation, etc., may contain essentially propylene as the olefin constituent. Higher temperatures of the order of 120° F. or over have been heretofore thought optimum for the sulfuric acid alkylation of isoparaffins with propylene, or with olefinic fractions predominating in propylene.

It has now been found that low boiling isoparaffins can be alkylated with propylene under substantially the same temperature conditions as used when alkylating C₄ olefins if a small amount of a butylene is present as a promoter of the alkylation reaction. The amount of butylene present should be between about 5% and 15%, and preferably about 10% by weight of the propylene. This proportion range of the promoter is critical and it is the discovery of this critical proportion range that is an important improvement in the art.

Either isobutylene or normal butylenes, or polymers of isobutylene or normal butylenes, may be used as promoters. It has been found, however, that isobutylene is somewhat more effective as an activator than normal butylenes. For ex-

ample, the alkylation reaction of propylene takes place in the presence of 10% of isobutylene at a temperature of about 65° F. whereas with 10% of butylene-2 a temperature of 75° to 85° F. is required. As illustrating the effect of varying percentages of isobutylene on the reaction, 5% requires a temperature of about 90° F., 10% a temperature of about 65° F. and 15% a temperature of about 60° F. to secure optimum yields of desired product.

For purposes of illustration, there is set forth below data obtained by the alkylation of isobutane with propylene alone and propylene in the presence of isobutylene.

Olefin charge	Propylene	90% propylene, 10% isobutylene	Propylene
Isobutane to olefin ratio	3:1:1	2.7:1	3.3:1
Per cent concentration of sulfuric acid	98.3	98.3	98.3
Acid to hydrocarbon dosage	2.1:1	1.8:1	2.2:1
Temperature ° F.	65	68	120
Time of addition of olefins			
minutes	60	60	60
Additional reaction time			
minutes	30	30	30
Per cent by weight of debutanized liquid, basis of olefin	78.6	220.2	215.5
Material balance	98.3	99.3	99.9
Per cent H ₂ SO ₄ in recovered acid	58.0	95.7	85.4
311° F. E. P. fraction:			
Per cent yield by weight, basis of olefin	65.5	185.9	164.1
Octane number C. F. R. M.		88.5	85.3
Bromine number	1	1	1

From the above data it will be observed that it is necessary to operate at about 120° F. to obtain a good yield of alkylation product when reacting isobutane with propylene alone. The results obtained by using a small amount of isobutylene as a promoter, however, even at 68° F., are much superior to the results obtained when using propylene alone, even at the higher temperatures. Thus the yield of 311° F. end point product when using a mixture of 90% propylene and 10% butylene is 185.9% as compared with 65.5% when operating under the same conditions with propylene alone and 164.1% when operating with propylene alone at 120° F. Moreover, acid deterioration is minimized with the activated mixture.

Further objects and advantages of the invention will become apparent to those skilled in the art from the following description of the invention wherein reference will be made to the accompanying drawing showing one form of apparatus for carrying out the process of the invention.

Referring to the drawing, an unsaturated gase-

ous hydrocarbon mixture, such as a refinery gas, comprising mainly C₃ and C₄ hydrocarbons, is charged through the line 1 to a fractionator 2. The hydrocarbons are fractionated to separate overhead a C₃ fraction containing a substantial amount of propylene, a side stream consisting primarily of isobutylene and C₄ olefins and substantially free from normal butane, and bottoms comprising the remainder of the C₄ fraction which contains substantially all the normal butane. Due to the close boiling points of butylene-2 and normal butane, the fractionation described above necessarily removes most of the butylene-2 along with the normal butane. The side stream containing the isobutylene necessarily includes most of the isobutylene and butylene-1 with the isobutylene predominating. The bottoms containing normal butane are withdrawn from the lower portion of the fractionator through the line 3. The C₃ fraction is withdrawn from the upper portion of the fractionator through the line 5 and introduced into an absorber 6. The gases in the absorber 6 are scrubbed with sulfuric acid to absorb the propylene. The unabsorbed gases comprising propane are released from the top of the absorber through the line 7, and may be passed to a propane dehydrogenation plant (not shown) from which the produced propylene-propane mixture may be charged to the absorber 6. The propylene acid mixture is withdrawn from the lower portion of the absorber through the line 9 and forced by the pump 10 through the line 11 to a reactor 12. The feature of absorbing a low-boiling olefin such as propylene in sulfuric acid followed by alkylation of the acid-olefin product with a low-boiling isoparaffin is disclosed and claimed in copending application, Serial No. 215,736, filed June 25, 1938.

The acid used in the absorption of propylene in absorber 6 is concentrated sulfuric acid of about 98% strength, which is introduced through the line 14 and forced by the pump 15 through the lines 16 and 17 into the upper portion of the absorber. While only one absorption tower is shown in the drawing, it is to be understood that two or more towers may be used.

The method of the acid absorption of the propylene from the C₃ fraction may vary. According to one method of operation the amount of propylene absorbed can be regulated to produce a substantially saturated solution of propylene in the acid. Another method of operation is to control the acid absorption so that a comparatively dilute solution of propylene and strong acid is obtained. It is preferable to carry out the operation according to the first method whereby there is less difficulty involved in the control of the absorption operation.

If a substantially saturated solution of propylene and acid is produced, then it is desirable to charge this rich absorbent mixture to an alkylation zone containing a quantity of additional fresh acid of alkylation strength to cause the propylene to enter into the alkylation reaction in the presence of the C₄ olefin promoter. This additional acid may be introduced into reactor 12 through the lines 20 and 22, or mixed with the acid absorbent mixture in the line 11 through the branch line 21 and the mixture then passed into reactor 12. In starting up the plant, it is desirable to first saturate this additional acid with isobutane and start feeding C₄ olefin before introducing the propylene-acid solution. If a dilute solution of propylene in the acid is obtained in the absorber, then it may be unnecessary to add

additional acid providing there is sufficient excess acid in the absorbent mixture to meet the requirements of sulfuric acid as a catalyst in the alkylation reaction in the reactor 12.

The side stream containing C₄ olefins and isobutane, referred to heretofore, is withdrawn at an intermediate point through the line 25 containing a pump 26 and passed to the reactor 12. The amount of the side stream is regulated to provide sufficient C₄ olefins to activate the alkylation of the isobutane with the propylene in the acid absorption mixture. Since the C₄ olefin content of the said side stream consists predominantly of isobutylene, the increased promotional effect of this iso-olefin is thereby obtained in a convenient manner. This amount should come within the critical range of about 5 to 15% of the propylene as referred to heretofore. The feature of absorbing propylene from a C₃ hydrocarbon fraction in sulfuric acid and then alkylating the acid-propylene absorption product with a low-boiling isoparaffin such as isobutane together with C₄ olefins under C₄ alkylation conditions is disclosed and claimed in copending application, Serial No. 253,052, filed January 27, 1939, now Patent No. 2,269,302, dated January 6, 1942.

It is preferable to maintain an excess of isobutane in the reactor 12, for example a ratio of isobutane to olefins of between about 3:1 and 5:1 or over, although as low a ratio as about 1:1 may be used. The amount of isobutane contained in the side stream withdrawn from the fractionator 2 is usually insufficient for this purpose and it is ordinarily necessary to add extraneous isobutane which may be done through the line 28.

In the reactor 12 the acid and hydrocarbons are intimately contacted by suitable agitation, such as with a stirrer 21. Sufficient pressure is maintained on the reactor to retain the hydrocarbons substantially in the liquid phase. A temperature of about 60° to 90° F. and preferably about 65° F. is used, although temperatures from zero to 100° F. may be used. A time of reaction of about 30 to 60 minutes and preferably about 45 minutes is required.

The reaction products are transferred from the reactor 12 through the line 29 to a settler 30 wherein the used acid is allowed to settle out in the lower portion thereof and may be withdrawn through the line 31. It is preferable to recycle a portion or all of the used acid by the pump 32 through the line 33, either to the reactor 12 through the branch line 35 or to the absorber through the branch line 36 and lines 16 and 17. A portion of the used acid may be recycled to the reactor 12 or absorber or both, while sufficient of the used acid is withdrawn from the system for recovery, and an equivalent amount of new acid added to maintain the acid in the system at the desired concentration. The feature of absorbing a low-boiling olefin in sulfuric acid, then alkylating the acid-olefin absorption product with a low-boiling isoparaffin in the presence of strong sulfuric acid of alkylation strength, and recycling used acid from the alkylation step to the absorption step is disclosed and claimed in the aforementioned copending application, Serial No. 215,736.

The hydrocarbons separate out in the upper portion of the settler 30 and are passed through the line 38 and pump 39 to a mixer 40 wherein the hydrocarbons are contacted with a neutralizing agent, such as an aqueous alkaline solution introduced through the line 41. The neutralization mixture is transferred from the mixer 40

through the line 42 to a settler 44 wherein the neutralizing agent is allowed to settle out and is withdrawn through the line 45. A portion or all of the used neutralizing agent may be recycled through the line 46 by the pump 47. The neutralized hydrocarbons collecting in the upper portion of the settler 44 are conducted through the line 48 to a stabilizer 50 wherein a stabilized motor fuel substantially free from isobutane is produced and withdrawn from the bottom of the stabilizer through line 51. The isobutane is taken overhead from the stabilizer through the line 52, compressed by the compressor 53 sufficient to cause condensation when the compressed vapors are chilled in the cooler 54. The isobutane condensate is then passed through the lines 55 and 28 to the reactor 12, for reuse in the alkylation reaction.

The acid absorption step may of course be omitted, and the alkylation of the propylene-containing mixture of hydrocarbons carried out under higher pressure to maintain the C₃ hydrocarbons in the liquid phase. The present invention is particularly adaptable for alkylating the excess C₃ olefins available in a plant which may already be equipped with a C₄ alkylation unit which is not constructed for the higher pressures required for C₃ alkylation in the absence of acid absorption. It will enable a C₄ alkylation unit to be constructed at lower cost. In such case, a separate C₃ alkylation unit of the required size to handle the available propylene may be added. This combination of separate C₄ and C₃ alkylation units also possesses the further advantage of overcoming fractionation difficulties involved in separating propane, isobutane and normal butane from off gases resulting from the stabilization of alkylation gasoline prepared from a mixed C₃ and C₄ charge containing substantial proportions of both C₃ and C₄ hydrocarbons as they normally occur in refinery gas.

In accordance with the present invention, the mixed C₃ and C₄ hydrocarbons of the refinery gas are separated by fractionation into mainly an overhead C₃ fraction rich in propylene and a bottom C₄ fraction containing substantially all of the n-butane. The C₃ fraction is supplied to the alkylation unit together with a small proportion of C₄ olefin required to promote this reaction as above described, and is alkylated with strong sulfuric acid in the presence of excess isobutane in the manner set forth above. The resulting alkylation gasoline is stabilized to separate liquid products from normally gaseous products, which in this case consist essentially of propane and isobutane. These off gases may be fractionated to separate the propane overhead from isobutane bottoms, and the isobutane then recycled to the alkylation unit. The C₄ fraction separated in the original fractionation as described above, may be supplied to the separate C₄ alkylation unit and alkylated in the normal manner for C₄ hydrocarbons. A small proportion of the C₄ fraction, consisting mainly of the lighter portion thereof containing isobutane and butylenes may be removed as a side stream from this main fractionator and supplied to the C₃ alkylation unit in the proportion required to promote the reaction in the manner described above.

By the use of acid absorption for the C₃ fraction separated in this main fractionator, a further advantage is obtained in the elimination of fractionation of the off-gases from the stabilization of the resulting alkylation gasoline. In such case, the acid absorption separates the propylene

from the propane of the C₃ fraction, prior to alkylation thereof; and the off-gas from the stabilization of the resulting alkylation gasoline then consists mainly of isobutane which can be recycled directly without fractionation to the C₃ alkylation unit.

Obviously many modifications and variations of the invention, as hereinbefore set forth, may be made without departing from the spirit and scope thereof, and therefore only such limitations should be imposed as are indicated in the appended claims.

We claim:

1. A process for the alkylation of a low boiling isoparaffin with propylene to produce high anti-knock liquid hydrocarbons within the gasoline boiling range, which comprises contacting propylene with a substantial molar excess of the low boiling isoparaffin in the presence of strong sulfuric acid of alkylation strength at temperatures of 60-90° F. and with an added 5 to 15% by weight based on the propylene of an olefin selected from the group consisting of the butylenes and low-boiling polymers thereof, whereby low-boiling isoparaffin is alkylated with the olefins to produce the liquid hydrocarbons.
2. A process according to claim 1 in which the added olefin is isobutylene.
3. A process for the manufacture of high anti-knock gasoline hydrocarbons from an olefin containing gas, the olefin content of which consists essentially of propylene, which comprises absorbing the propylene in strong sulfuric acid, separating unabsorbed gas from the propylene-acid solution, saturating additional fresh strong sulfuric acid with isobutane, introducing the propylene-acid absorption product into the additional fresh acid containing isobutane, and alkylating at a temperature of 60-90° F. the propylene-acid absorption product in this mixture in the presence of excess isobutane and about 5-15% by weight based on the absorbed propylene of added olefins selected from the group consisting of butylenes and low-boiling polymers thereof, whereby the isobutane is alkylated with the olefins to produce the gasoline hydrocarbons.
4. A process for the manufacture of high anti-knock gasoline hydrocarbons from a refinery gas consisting essentially of a mixture of C₃ and C₄ hydrocarbons, which comprises fractionating the gas to separate the same into a C₃ fraction containing propylene, a heavier C₄ fraction containing substantially all of the normal butane and a light C₄ fraction consisting mainly of isobutane and C₄ olefins predominating in isobutylene and substantially free from normal butane, alkylating the separated C₃ fraction at a temperature of about 0-100° F. with strong sulfuric acid of alkylation strength in the presence of excess isobutane and with the addition of a sufficient proportion of the said light C₄ fraction to provide about 5-15% by weight based on the propylene of C₄ olefins predominating in isobutylene, whereby the isobutane is alkylated by the olefins to produce the gasoline hydrocarbons, stabilizing the resulting alkylation products to separate normally liquid products from normally gaseous products consisting essentially of isobutane and propane, fractionating the normally gaseous products to separate isobutane from propane, and recycling separated isobutane to the alkylation reaction.
5. A process for the manufacture of high anti-knock gasoline hydrocarbons from a refinery gas consisting essentially of mixed C₃ and C₄ hydro-

carbons, which comprises fractionating the gas to separate the same into a C₃ fraction containing propylene, a heavier C₄ fraction containing substantially all of the normal butane, and a lighter C₄ fraction containing isobutane and C₄ olefins predominating in isobutylene and substantially free from normal butane, contacting the separated C₃ fraction with strong sulfuric acid to absorb the propylene and separate the same from propane, alkylating the propylene-acid absorption product at a temperature of about 0-100° F. in the presence of strong sulfuric acid of alkylation strength with excess isobutane and a sufficient proportion of the said lighter C₄ fraction to provide about 5-15% by weight based on the absorbed propylene of said C₄ olefins predominating in isobutylene, whereby the isobutane is alkylated with the olefins to produce the gasoline hydrocarbons, separating hydrocarbon alkylation products from used acid, stabilizing the hydrocarbon alkylation products to separate normally liquid products from normally gaseous products consisting essentially of isobutane, and recycling separated gaseous products to the alkylation reaction.

6. A process for the alkylation of a low-boiling isoparaffin with propylene to produce high anti-knock liquid hydrocarbons within the gasoline boiling range, which comprises contacting propylene with a substantial molar excess of the low-boiling isoparaffin in the presence of strong sul-

furic acid of alkylation strength at temperatures of 60-90° F. and with an added C₄ olefinic fraction providing 5 to 15% by weight based on the propylene of C₄ olefins.

5 7. A process according to claim 6 in which the C₄ olefins of said added fraction predominate in isobutylene.

8. In the manufacture of high anti-knock gasoline hydrocarbons by the alkylation of isobutane with a mixture of C₃ and C₄ olefins in the presence of strong sulfuric acid, the improvement which comprises fractionating a hydrocarbon gas containing a mixture of C₃ and C₄ olefins and paraffins to separate a C₃ fraction containing propylene, and a light C₄ fraction containing isobutane and C₄ olefins predominating in isobutylene and largely free from normal butane, blending the C₃ fraction with a proportion of said light C₄ fraction to provide sufficient C₄ olefins predominating in isobutylene to activate the alkylation of isobutane with propylene at temperatures below about 100° F., and then alkylating isobutane with the resultant mixture of C₃ and C₄ olefins at temperatures within the range of 0-100° F. in the presence of strong sulfuric acid.
